INDICATING CONTROL KNOB

Albert A. Seasongood, Melrose Park, Pa., assignor
to Leeds and Northrup Company, Philadelphia,
Pa., a corporation of Pennsylvania

Application March 14, 1947, Serial No. 734,808

4 Claims. (Cl. 116—124)

1

This invention relates to control knobs for multi-position switches, valves and the like, and particularly to control knobs having associated indicia identifying its various control settings.

In accordance with the invention, the control knob is provided with an internal dial member having position-indicating characters or markings successively individually visible through a window or aperture in the knob as it is rotated to its various control settings. Though requiring less panel space than the usual control knob constructions having external dials and pointers, there is no loss of readability. Moreover, as only one symbol or group of symbols is visible at any one time, there can be no uncertainty of the knob setting.

More particularly, the numerals, letters or other symbols or indicia are arranged on the surface of a cone-shaped dial member so mounted for rotation, both about its own axis and that of the knob, that the individual symbols or characters successively appear each in the same or upright position immediately in back of a window in the center of the knob.

Further in accordance with the invention, the drive for the dial is also within and concealed by the knob outline, so that all that is visible is the knob with its single dial reading. The elimination of distracting visible detail focuses attention of the observer upon the dial reading; this is particularly helpful when the controlled device, as in the case of Wheatstone bridges, potentiometers, multi-point switches, and the like, is provided with a plurality of control knobs whose settings must be frequently changed and read.

The invention further resides in features of construction, combination and arrangement hereinafter described and claimed.

For more detailed understanding of the invention, reference is made to the accompanying drawings, in which:

Fig. 1 is a perspective view of a control knob embodying the invention;

Fig. 2 is a sectional view on enlarged scale of the control knob of Fig. 1;

Fig. 3 is an exploded view showing components appearing in Fig. 2;

Fig. 4 is a sectional view on enlarged scale showing a different internal construction of the knob of Fig. 1; and

Fig. 5 is an exploded view showing parts appearing in Fig. 4.

In the usual control knob arrangement used for manipulation of switches, valves and the like, there is attached to it a dial having characters or

2

symbols, all concurrently visible to an observer, which for different settings of the knob are successively opposite a stationary index; alternatively, there may be attached to the control knob a pointer which for different settings of the knob is opposite various legends, symbols or markings, indicating the control setting. Such arrangements occupy considerable panel space, and in addition there is ever present the possibility an observer, because of haste or inexperience, will improperly read the setting.

Though the invention is not limited thereto, there are herein disclosed two control knobs of similar external appearance but of somewhat different internal construction. As shown in Fig. 1, there is visible to the operator or observer a control knob 10 having a window or opening through which successively appear numerals or other indicia uniquely identifying the setting of the knob. There is no external dial or pointer arrangement which would not only occupy much greater panel space but would create the possibility of confusion in reading of the knob settings.

The details of internal construction of one suitable dial and operating mechanism therefor is shown in Figs. 2 and 3. The knob shell 12, of size suitable to be conveniently grasped and manipulated by the operator, is hollow and its upper face, as viewed in Fig. 2, is provided with a central aperture or window 11 preferably closed for exclusion of dust by a pane 13 of transparent material, such as Celluloid or the like. The shell 12 may be of any suitable material, metallic or otherwise; for example, it may be of molded insulating material, particularly when used to control the setting of the shaft of electrical switches or contact members. To the ledge member 14 suitably secured within the shell 12, or formed integrally therewith, is fastened, as by screws 15, a coupling bracket 16 suited to receive the shaft 17 of a switch or other device to be controlled. A set screw 18, or equivalent, is used to hold the control knob to the shaft 17. The dial member 19, in the specific arrangement shown in Figs. 2 and 3, is in the form of a truncated cone with the dial markings spaced angularly on the surface of the cone. The dial member 19 is mounted for rotation on the jack shaft 20 carried by, or integral with, the coupling bracket 16. The axis of the jack shaft 20 is inclined at such angle with respect to the axis of rotation of shaft 17 that as the dial member 19 is rotated, the dial markings in turn appear beneath the window 11.

Axial movement of the dial member along the

jack shaft may be prevented by a heading over the free end of the shaft, or by using a restraining screw between whose head and the dial member 19 there is interposed a thrust washer 21. For effecting rotation of the dial member 19, there may be attached thereto, or formed integrally therewith, a bevel gear member 22, or equivalent.

All of the elements thus far described form a knob assembly which is detachable as a unit from the controlled shaft 17. The hole 23 provided in the shell 12 permits insertion of a screw driver or other tool for loosening or tightening of the set screw 18 which normally holds the knob assembly to the shaft 17.

To effect rotation of the dial member 19, with respect to the knob as the knob is turned about the axis of shaft 17, there is provided a stationary gear member 24 which in the particular construction shown slips over the shaft bushing 25 and is held against the front face of the panel 26 by the clamping nut 27 used to hold the bushing 25 in place. Additionally, to prevent accidental movement of the gear 24, it is provided with a locking tip 28, which may be pressed out from the gear blank itself, received by a slot or opening 29 in the instrument panel 26. Preferably, and as shown, the stationary gear 24, as well as all of the other dial operating parts, are concealed within the knob 10 so that the only movable part visible to the operator is that restricted portion of the dial member 19 visible through the window 11.

The numerals or letters on the dial member 19 are so positioned that although the dial rotates both about its own axis, that is, the axis of the jack shaft 20, and the axis of the shaft 17, the successive markings or indicia, nevertheless always appear in the same position with respect to the observer so clearly to identify the particular circuit or circuit element in use, or the particular setting of a valve or other controlled element. The central location of the window in the domed face of the knob with the dial face immediately behind it provides an unobstructed view of the dial symbols and for best visibility under existing light conditions.

In addition to the operating advantages above mentioned, it should also be noted that the knob may be used with devices already installed for use, in replacement of other types, merely by clamping the gear 24 in place and putting the knob 10 on the shaft 17; no access to the reverse side of the panel or to the interior of the enclosure including it is required.

The control knob arrangement shown in Figs. 4 and 5 is generally similar to that of Figs. 2 and 3, and accordingly the corresponding parts are identified by the same reference characters. The main difference between the two constructions is that in the modification of Figs. 2 and 3, the stationary gear 24 is held against the panel 26 and, is not removable with the knob 10, from the control shaft 17, whereas in the modification of Figs. 4 and 5, the stationary driving gear 24A is part of the knob assembly detachable as a unit from the controlled shaft 17. With the construction of Fig. 4, the proper clearance for smooth operation of gears 22 and 24A is adjusted once and for all at the factory, whereas with the construction of Fig. 2, the proper clearance must be re-established whenever the knob 12 has been loosened on shaft 17.

A modified form of dial member and method of mounting it is also shown in Fig. 4. In this modification, the jack shaft 20A is separate from

the coupling bracket 16A and is provided with a threaded end 30 received by the boss 31 of the bracket 16A. The dial plate 32 on which the position-setting characters appear is separate from the body member 34 and is detachably held thereto by a plurality of screws 33; this type construction is of advantage in that to adapt the construction for various uses it is only necessary to carry in stock differently marked inexpensive cones 32 rather than relatively expensive casting and gear assemblies 34-22. The two members 32 and 34 comprise dial member 19A.

In the construction of Figs. 4 and 5, the lower end of the coupling member 16A is of reduced diameter to pass through the opening 36, Fig. 5, in the upper end of the cone-shaped member 35 to which is secured the driving gear member 24A. The member 37 which threadably engages the reduced end portion 38 of the coupling member 16A, cooperates therewith to provide a groove in which the cone-shaped member 35 is free to rotate with respect to the knob 10 as a whole. The cone member 35 is provided with a notch 39 which receives, when the knob is slipped in place on the control shaft 17, the locking tip 40 which is bent upwardly from the disc 41 clamped against the panel 26 by the nut 27. To prevent accidental rotation of the locking plate 41, it may be provided with the tips 28A bent downwardly therefrom and received by the slots or openings 29 in the panel 26; the openings 29 are preferably at different distances from the axis of shaft 17 so that there is only one position of plate 41 for which the tips 28A and openings 29 are in register. There is thus defined a single position at which the notch 39 of gear-cone 35 will engage the tongue 40 of plate 41. Thus, to insure proper correspondence between the dial indications and the angular positions of shaft 17, it is only necessary, in replacing the control knob, to make certain the set-screw 18 engages the usual depression or flattened area of the shaft, and the tongue 40 engages with the slot 39.

As the knob 10 is rotated by the operator to the various control settings of the switch, or other member actuated by shaft 17, the dial member 19A rotates about the axis of shaft 17, and also because of the engagement between the gears 22 and 24A rotates about its own axis, that is, the axis of the jack shaft 20A, thus in succession to move the various dial markings into view through the window 11. As with the modification of Figs. 2 and 3, all of the driving mechanism of the dial is concealed within the knob, and there is visible to the observer only the marking indicating the position of the associated device or equipment. All other moving parts which would distract the observer are hidden and are within the knob itself, so affording compactness not attainable with constructions using external dials and pointers. Furthermore, as with the modification of Figs. 2 and 3, the knob may be installed without any need for access to the reverse face of the panel 26.

It shall be understood the invention is not limited to the particular arrangements specifically disclosed and that changes and modifications may be made within the scope of the appended claims.

What is claimed is:

1. An arrangement comprising a hollow control knob having a window in its face, a conical dial member having indicia successively visible through said window, structure for supporting said dial member within said knob for rotation

therewith and for rotation about an axis inclined with respect to the axis of rotation of the knob, a driven member attached to and rotatable with said dial member, and a stationary driving member operatively engaging said driven member to effect rotation thereof about its said inclined axis as said knob is rotated about its own axis.

2. A hollow knob assembly detachable as a unit from a shaft to be controlled comprising a dial member rotatably mounted within said knob and having indicia successively visible through a window in the knob face, a gear rotatable with said dial member, and a second gear mounted within said knob concentric with its axis of rotation for driving engagement with the first gear and suited detachably to engage a locking member preventing its rotation when the knob is on said shaft.

3. A hollow knob assembly having a window around the central axis thereof, means for attaching said knob assembly to a shaft extending axially of said assembly, a dial member within said hollow knob, means supporting said dial member for rotation about an axis inclined to that of said knob assembly for rotation of said dial member past said window, and a driving connection effective upon rotation of said knob to move said dial member relative to said window.

4. An arrangement for effecting rotation of a

5

10

15

rotatable shaft and indicating the position thereof comprising a hollow control knob having a window which is centrally located at the axis of rotation of the knob, means for securing said knob to said rotatable shaft, a dial member within said knob and having angularly spaced indicia, structure for supporting said dial member within said knob for rotation about its own axis and for rotation around the axis of the knob, and means including a stationary member having a driving connection with said dial member effective upon rotation of the knob and dial member about the axis of rotation of the knob to effect rotation of said dial member about its own axis successively to present said indicia to said central window of the knob.
